UNITED STATES PATENT OFFICE.

JAMES J. CARNES, OF MALDEN, AND WILLIAM T. STRONG, OF EVERETT,
MASSACHUSETTS.

ICE-CUTTER FOR RAILWAY-CARS.

1,148,754.

Specification of Letters Patent. Patented Aug. 3, 1915.

Application filed February 23, 1915. Serial No. 9,953.

To all whom it may concern:

Be it known that we, JAMES J. CARNES and WILLIAM T. STRONG, citizens of the United States, and residents of Malden and 5 Everett, respectively, in the county of Middlesex and State of Massachusetts, have invented an Improvement in Ice-Cutters for Railway-Cars, of which the following description, in connection with the accompanying drawings, is a specification, like characters on the drawings representing like parts.

This invention relates to an ice cutting mechanism especially adapted for cutting ice on the road beds of street railways, and 15 has for its object to provide a novel cutting mechanism, which is capable of being applied to an electric railway car and particularly to the snow plow now commonly used, so that the cutters may be forced through 20 the layer of ice on the road bed, with a minimum of power and without diminishing to any material extent the traction of the wheels of the snow plow upon the rails.

The invention further has for its object 25 to provide a cutting mechanism, which can be secured to the shear of the snow plow, so as to be raised and lowered with said shear.

Provision is made for adjusting the cutters with relation to the road bed so as to 30 regulate the depth of the cut made in the ice. Provision is also made for shielding the motorman from the spray of fine ice. Provision is also made to permit the cutting 35 mechanism to be attached to an inclined shear and yet allow the cutters to occupy a position in the same horizontal plane.

These and other features of this invention will be pointed out in the claims at the 40 end of this specification.

Figure 1 is a plan view of a portion of a snow plow provided with an ice cutting mechanism embodying this invention, and Fig. 2, a side elevation of the mechanism 45 shown in Fig. 1.

Referring to the drawings, *a* represents the shear member of a snow plow of ordinary construction, such as is now commonly used on electric street railways, and only a 50 portion of which is herein shown. The shear member *a* has connected with it mechanism for cutting ice on the road bed, which mechanism is preferably made as herein shown, and consists of a carrier or bar *b* extended 55 transversely of the track upon which the

snow plow runs, and provided with a plurality of cutters *c*, which are and may be individually secured to the bar *b* by set screws *d* or otherwise, and are inclined downwardly toward the road bed. The 60 lower or free ends of the cutters *c* are suitably sharpened. The cutter carrying bar *b* is preferably made longer than the width of the track, and is fastened to a supporting frame, which is herein shown as substantially parallel metal bars 10, 12, connected by an intermediate cross bar 13, the bars 10, 12 being pivotally connected at their rear ends to brackets 14, 15, bolted or otherwise fastened to the front face of the shear member *a*. The supporting bars 10, 12, are provided at their front ends with upwardly inclined extensions or arms 16, to which is bolted or otherwise adjustably secured a device to position the cutters with relation to 75 the road bed, so as to regulate the depth of cut into the ice. The positioning device may be made as herein shown and consists of a skid or board 20, which is fastened to the upwardly inclined arms 16 of the supporting 80 bars 10, 12, by bolts 21, and the skid 20 may be lowered away from the inclined arms 16 of the said bars by means of shims 22 interposed between said bars and skid. The skid or board 20 may be supported at its center 85 by a link chain 23, which is engaged with an eyebolt 24 secured to the skid, and with a shackle 25 attached to a link or bar 26, extended through a slot 27 in the shear member and pivoted at its rear end to a crank 90 28 on a rock shaft 29, which is provided with cranks or arms 30, to which the shear member *a* is bolted or otherwise fastened.

The crank shaft 29 is designed to be rocked by an operator within the car body 31, by 95 means of suitable mechanism such as now commonly used on snow plows for raising and lowering the shear member, and only a portion of which is shown, namely the link or rod 32.

From the above description, it will be seen that by rocking the shaft 29, the shear member *a* may be raised or lowered with relation to the road bed, and that the cutting mechanism is raised and lowered with the 105 shear member. When the shear member *a* is lowered into its operative position, the cutting mechanism is also lowered until the rear or lower end of the skid 20 rests on the layer of ice on the road bed, and by reason 110

of the cutter frame being pivoted to the shear member, the latter can be lowered after the skid rests upon the ice, so as to bring its lower edge into position to remove the ice cut by the cutters.

When the skid rests on the upper surface of the layer of ice covering the road bed, the cutting edges of the cutters are projected into the layer of ice a predetermined distance, and said cutters are pushed through the ice so as to remove the same down below the level of the upper surface of the rails, and the distance the cutters penetrate the ice may be regulated by adjusting the skid with relation to its supporting frame, so as to insure that the power of the snow plow will force the cutters through the ice, without diminishing the traction of the wheels of the snow plow upon the rails 40 of the track. 20 In other words, the skid 20 prevents the cutters penetrating the layer of ice to such depth as would offer sufficient resistance to the movement of the snow plow, as to lift the snow plow and reduce the weight of the latter upon the car wheels, and thereby diminish the traction of the car wheels upon the rails, which in some cases would be sufficient to cause the car wheels to slip upon the rails and not propel the snow plow forward, consequently rendering the cutting mechanism inoperative for the purpose intended, and at the same time causing a loss of power, as the current would be wasted in merely spinning the car wheels.

35 By making the skid 20 adjustable with relation to the cutter supporting frame, by means of the shims 22 or otherwise, the depth of the cut into the ice can be regulated, and also the cutters may be ground or 40 sharpened without materially varying the distance the cutters penetrate into the layer of ice.

Provision is also made for protecting the view of the motorman operating the plow, 45 and for this purpose a shield or guard in the form of a substantially wide board 42 is located above the cutters, and is secured to brackets 43 which are fastened to the side bars 10, 12, of the frame which supports the cutters.

The guard or board 42 serves to prevent the fine ice from being thrown upward into the field of sight of the motorman, and insures the latter a clear view of the track in 55 front of the snow plow, thereby reducing the liability of accidents.

The side bar 12 of the supporting frame is connected with the bracket 15, by a pin and slot connection, the pivot pin 50 for the bar 12 being capable of moving in a vertical slot 51 in the bracket 15. This arrangement enables the cutting mechanism to be applied to the shear *a* of snow plows as now commonly constructed, in which the shear is 60 arranged so as to incline downwardly from

its rear toward its front end, when the shear is in its elevated position, and when so applied, the rear end of the shear is capable of descending after the front end of the shear rests on the road bed, which enables the skid 70 to assume a horizontal position with the cutter bar level or in a plane parallel with the road bed, so as to insure all of the cutters being brought into the desired or operative position. 75

The skid 20 is lifted above the road bed when not in use, by the bar 26 which is supported by and moves with the shear *a*, and the weight of the cutting mechanism may be sustained by the shear *a* directly as herein represented, or it may be otherwise sus-

Claims—

1. The combination with a snow plow provided with a vertically movable shear, of an 85 ice cutting mechanism located in front of said shear and comprising a cutter carrying bar extended transversely of the snow plow, cutters secured to said bar, a supporting frame for said cutter-carrying bar pivotally 90 attached to said shear to move vertically, a skid attached to said frame, and a shield supported by said frame above said cutter carrying bar.

2. The combination with a snow plow provided with a vertically movable shear, of an 95 ice cutting mechanism located in front of said shear and comprising a cutter-carrying bar extended transversely of the snow plow, cutters secured to said bar, a supporting 100 frame for said cutter carrying bar pivotally attached to said shear to move vertically, and a skid attached to said frame.

3. The combination with a snow plow provided with a shear extended transversely of 105 the snow plow in front of the same, of an ice cutting mechanism located in front of said shear and capable of being moved vertically independently of said shear and comprising a cutter carrier pivotally extended 110 transversely of the snow plow, a cutter carried thereby, and a supporting frame for said cutter carrier attached to said shear.

4. The combination with a snow plow provided with a vertically movable shear, of an 115 ice cutting mechanism comprising a supporting frame pivotally attached to said shear and projecting in front thereof, a cutter carried by said supporting frame, and means carried by said supporting frame in front of 120 said cutter for positioning the cutter with relation to the road bed.

5. The combination with a snow plow provided with a vertically movable shear, of an 125 ice cutting mechanism comprising a supporting frame attached to said shear and projecting in front thereof, a cutter carried by said supporting frame, means for positioning the cutter with relation to the road bed, and a shield located above said cutter. 130

6. An ice cutting mechanism of the character described, comprising a cutter bar, a plurality of cutters secured thereto, a supporting frame for said cutter bar, and a skid attached to said frame in front of said cutter bar.

5 In testimony whereof, we have signed our

names to this specification in the presence of two subscribing witnesses.
